Assistant Examiner — Ian F Whitmore

(57) **CLAIM**

The ornamental design for a display panel with graphical user interface, as shown and described.

DESCRIPTION

FIG. 1 is a front view of a portion of a display panel with a graphical user interface according to a first embodiment of a new design; and,

FIG. 2 is a front view of a portion of a display panel with a graphical user interface according to a second embodiment of our new design.

In all figures, the outermost broken-line square illustrates the perimeter of a portion of a display panel, and defines the bounds of the claimed design. The remaining broken lines illustrate portions of a graphical user interface. The broken lines form no part of the claimed design.

1 Claim, 2 Drawing Sheets
